UNITED STATES PATENT OFFICE

139,714

DESIGN FOR A COMBINATION DRESSER, VANITY, AND DESK

Alexander C. Rindskopf, Wilmette, Ill.

Application September 20, 1944, Serial No. 115,371

Term of patent 7 years

(Cl. D33—7)

To all whom it may concern:

Be it known that I, Alexander C. Rindskopf, a citizen of the United States, residing at Wilmette, in the county of Cook and State of Illinois, have invented a new, original, and ornamental Design for a Combination Dresser, Vanity and Desk, of which the following is a specification, reference being had to the accompanying drawing, forming part thereof, wherein:

ward the front and one end of a combination dresser, vanity and desk, showing my new design;

Fig. 2 is a front elevation thereof; and

Fig. 3 is an elevation of the end thereof which appears in Fig. 1.

I claim:

The ornamental design for a combination dresser, vanity, and desk, as shown.

ALEXANDER C. RINDSKOPF.
